(57) **CLAIM**

The ornamental design for a shopping bag, as shown and described.

DESCRIPTION

FIG. 1 is a perspective view of a shopping bag in accordance with the present design when in a folded, closed configuration;

FIG. 2 is a right side view thereof;

FIG. 3 is a left side view thereof;

FIG. 4 is a front view thereof;

FIG. 5 is a back view thereof;

FIG. 6 is a top view thereof when in an unfolded configuration;

FIG. 7 is a bottom view thereof when in an unfolded configuration; and,

FIG. 8 is a perspective view thereof when in a folded, open configuration.

The shading represents contour of the claimed design.
